UNITED STATES PATENT OFFICE.

WILLIAM H. BERGER, OF PHILADELPHIA, PENNSYLVANIA.

EAVES-TROUGH HANGER.

SPECIFICATION forming part of Letters Patent No. 339,847, dated April 13, 1886.

Application filed October 19, 1885. Serial No. 180,250. (No model.)

To all whom it may concern:

Be it known that I, WILLIAM H. BERGER, a citizen of the United States, residing at Philadelphia, in the county of Philadelphia 5 and State of Pennsylvania, have invented certain new and useful Improvements in Eaves-Trough Hangers; and I do hereby declare the following to be a full, clear, and exact description of the invention, reference being had 10 to the accompanying drawings, which form a part of this specification, in which—

Figure 1 is a side view of the hanger. Fig. 2 is a front view. Figs. 3, 4, and 5 are detail views.

15 My invention relates particularly to suspension eaves-trough hangers, (meaning thereby hangers in which the support is above the trough,) and has for its object, principally, to provide means for fastening the trough to the 20 hanger and permitting its removal therefrom, to obtain facilities for adjustment to troughs having beads of different diameters, and for securing the necessary fall or incline of the latter.

25 My invention consists in the peculiar construction and combination of parts hereinafter fully set forth, having reference particularly, first, to means for fastening the trough in place on the iron; second, to means whereby the 30 fastening is rendered adjustable to fit troughs beads of different diameters, and, third, to means for adjusting the hanger to secure the fall or inclination of the trough, all as herein-after fully set forth.

35 Referring to the accompanying drawings, A represents the hanger, which is made in two parts, B and C. The part B is the shank, and consists of the vertical portion B', having adjusting-holes b', and the incline B², which rests 40 on the roof when in use, (either above or below the shingles,) and is formed with holes b² for the reception of nails, by which it is secured in position. The ribs b form a groove or guide, b³, on the part B'. The part C is 45 substantially in the form of an inverted T, having a central standard, C', and a cross-bar, C², having two arms or branches, C³ and C⁴. The standard C' has adjusting-holes c, which register with those in the vertical portion B' 50 of the shank, a bolt, D, serving to hold the said parts together in any adjusted position,

and it has studs or blocks c', which enter the grooves b³ in said part B'. The holes in said part B' are only one-half as far apart from each other as are the holes in the standard C' from each other, so that by moving the part C on part B a distance only equal to one half the distance between any two adjoining holes in the standard C' two holes, one in the portion B' and one in standard C', will be brought into 60 exact registration. By means of the facilities for adjustment thus provided the eaves-trough supported on hangers thus constructed can be very evenly or regularly adjusted to have any fall or pitch desired. It will be noted that the standard C' is of considerable length, as is also the part B', so that a long range of 65 adjustment is secured by sliding the parts on one another. Also, that a fine adjustment can be secured by reason of the slight distance 70 that the part B requires to be moved in order to secure the transfer of the fastening-bolt from one registering opening to another. It will further be noted that the standard C', being wholly above the trough, (the latter, as 75 hereinafter described, being below or on the under side of the cross-bar C²,) it does not, nor does any part of it, dip or extend into said trough, and hence forms no impediment to collect chips, dirt, &c., or prevent the free 80 flow of the water. The shank B is formed so that its part B', when on the roof, has its flat side or widest part in the plane of the roof, while the part B' is in a plane at right angles thereto, so that its edges or thinnest sides are 85 in the plane of the wall of the house—in effect the same as if a quarter-twist were given to the iron. The standard C' stands in the same plane as and parallel with the part B'—that is, both parts stand with their edge to the 90 front—the cross bar C² resting, also, with its flat sides in a vertical plane and its edges horizontal. By these means the edges of said parts B' C' C² are presented to any snow or ice falling or sliding off the roof to which the hanger 95 is applied, so that strength is secured, danger of breakage avoided, and but small surface presented for contact with such snow or ice.

The end of the arm C³ has a notch or slit, c², in which is an offset, c³. This slit or notch receives the inner edge, e, of a trough, E, which is securely fastened by driving in or in-

outer end of the arm C has a beaded edge, which receives the outer turned edge of the trough E.

5 To hold the bead e' in the trough hook, I provide the thimble G, and form on the upper side of the arm C³ a notch or series of notches or teeth, $h h$. The thimble G is of the peculiar shape shown, having a flaring bore or opening, g , through which passes the arm C⁴, a lip, g' , which bears against the curled or turned edge of the trough E, another lip, g^2 , which bears against the under side of the arm C⁴, and a ring-segment or strap, g^3 , which passes over the upper edge of said arm C⁴ and rests against the vertical side or shoulder of one of the notches or teeth h . In this position, which is that shown in full lines in Figs. 1 and 2 of the drawings, the trough cannot come out of the hanger.

When it is desired to insert a trough in the hanger, or to remove the trough, the thimble G is turned one half around on the arm C⁴, as shown in dotted lines in Fig. 1 of the drawings, with the lips $g' g^2$ on the upper side of said arm. In this position the thimble G, its front being slightly inclined from the perpendicular, may be slid back on the arm C⁴ sufficiently to clear the curled edge or bead of the trough, and to permit the latter to be inserted in or removed from the hanger, the work of insertion and fastening, or of release and removal, being readily done. One notch on the arm C³ will be sufficient for securing a trough in place on the hanger with the thimble G; but to render the fastening adjustable to troughs the beads of which vary in diameter I provide several such notches or teeth, as shown. When the thimble G is turned down, it may, by duly adjusting it in the notches h , be caused to bear with considerable pressure against the bead-trough.

What I claim as my invention is as follows:

tion being on planes, and said part B' having a notch or slit and offset for the reception of the edge of a trough and a key or fastener therefor, substantially as shown and described.

2. In a suspension eaves-trough hanger, the cross-bar, C², having at its inner end a notch or slit and offset for the reception of the edge of a trough and a key or fastener therefor, substantially as shown and described.

3. In a suspension eaves-trough hanger, the combination, with shank B, having vertical 60 part B' and incline B², said parts standing in planes at right angles to each other, of part C, composed of standard C' and cross-bar C², said part C being in a plane with the part B' and adjustably fastened thereto, and said cross-bar 65 having means for securing a trough to its under side, substantially as shown and described.

4. The combination, with the eaves-trough iron C, having a bend or hook, c', and a notch or tooth, h, of a thimble, G, substantially as 70 shown and described.

5. The combination of an eaves-trough hanger having a hook or bend for receiving the bead or curl of a trough, E, and a series of notches or teeth, of a thimble, G, whereby 75 an adjustable fastening for said trough is provided, substantially as set forth.

6. In an eaves-trough hanger, a fastening consisting of a sliding thimble, G, having an opening or bore for the passage of the hanger-iron and two lips, substantially as shown and described.

In testimony that I claim the foregoing I have hereunto set my hand.

WILLIAM H. BERGER.
